[57] CLAIM

The ornamental design for a top portion for a flexible bag with sealed end and recloseable seal, as shown and described.

DESCRIPTION

FIG. 1 is a front elevation view of a top portion for a flexible bag with sealed end and recloseable seal showing our new design;

FIG. 2 is a rear elevation view thereof;

FIG. 3 is a cross-sectional view taken along line 3—3 thereof;

FIG. 4 is a cross-sectional view thereof, with the seal in an open position; and,

FIG. 5 is a side elevation view thereof; the opposite side being identical.
